UNITED STATES PATENT OFFICE

ELDEN O. HENDERSON, OF McALLEN, TEXAS

DISPLAY CABINET

Application filed September 13, 1927. Serial No. 219,298.

This invention relates to display cabinet and more particularly to a device of this character especially adapted for use in self-service stores.

5 An important object of the invention is to provide a display cabinet so constructed that the goods may be readily arranged thereon and bins provided upon the top for the reception of goods which are adjustable as to 10 size to accommodate the amount of goods which it is desired to exhibit.

A further object of the invention is to provide a device of this character so constructed that it is readily possible to associate the 15 national magazine advertising employed by present day manufacturers with the goods exhibited thereon.

A further object of the invention is to provide a device of the type just described which 20 is additionally constructed to permit association with the goods and the national advertisement thereof, dealers' comments or prices.

A still further object of the invention is to provide a display cabinet which readily lends 25 itself to use in positions where it is back against the wall or to use in positions where cabinets are arranged back to back and serve as a partition in the store.

A still further object of the invention is 30 to provide a display device for national advertising adjustably associated with a counter of this character and so constructed that it will support the advertisement either upon one or both surfaces, thus permitting its use 35 with counters when employed in either capacity.

These and other objects I attain by the construction shown in the accompanying 40 drawings, wherein for the purpose of illustration is shown a preferred embodiment of my invention and wherein:—

Figure 1 is a fragmentary view in elevation illustrating a display cabinet constructed in 45 accordance with an embodiment of my invention;

Figure 2 is a sectional view taken substantially on the line 2—2 of Figure 1;

Figure 3 is a detail sectional view taken 50 substantially on the line 3—3 of Figure 1;

Figure 4 is a view in perspective of a partition strip herein employed unapplied;

Figure 5 is a transverse section through a modified form of display cabinet;

Figure 6 is a perspective view of the display easel;

Figure 7 is a vertical sectional view through the advertising frame or display frame shown in Figure 1.

Referring to the drawings and more particularly to the wall type of counter, the numeral 10 generally designates sills or base beams to which, at one end, are secured front studding 11 and at the opposite end back studding 12 which are of considerably greater length than the studding 11. To the upper ends of the front studding 11 are secured the forward ends of display cabinet beams which extend horizontally and have their rear ends secured to the studding 12. 55 These beams 13 support a display cabinet top 14, the rear edge of which is slightly spaced from the forward faces of the rear studding 12 to provide a space for the reception of the lower end of a blackboard 15. Applied to the upper ends of the studding 12 is a plate 16, to the upper surface of which are secured front and rear rails 17 and 18 spaced to provide a groove 19 therebetween. Secured to the sill 16 and the forward rail 17 60 and clamping the upper edge of the blackboard 15 thereto is a spacing strip 20 having its upper edge coplanar with the rails 17. Secured to the forward face of the spacing strip 20 is a finishing strip 21 which has 65 its upper edge coplanar with the upper edge of the spacing strip and is of greater depth than the spacing strip so that its lower margin confronts the blackboard in spaced relation thereto.

70 The numeral 22 designates partition strips, to the rear edges of which are secured vertically extending securing bars 23. Each securing bar 23 has its lower end extending below the lower edge of the associated partition 22 and has its upper edge beveled upwardly from its rear to its front face, as indicated at 24. The upper surface of the display cabinet top 14 immediately in advance 75 of the blackboard is provided with a groove 80

25 for the reception of the projecting lower end of the securing bars and the securing bars are of such length that when they are seated in these grooves, the upper ends of their forward faces project beyond the lower edge of the finishing strip 21. However, because of the bevel cut at 24, the securing bar may be entered behind the finishing strip, as indicated in dotted lines in Figure 2, to 10 permit the finishing bar to be moved into alignment with the groove. These partitions are in this manner rendered both adjustable longitudinally of the top and bodily removable therefrom. Side faces of the 15 partition adjacent the forward ends thereof are provided with grooves 26, which incline upwardly and forwardly from the lower to the upper edge of the partition. The grooves of adjacent faces of adjacent partitions are 20 adapted to receive the edges of a panel 27 which may be of glass and which combines with the partition to provide a bin for the reception of loose articles, such as fruit, vegetables and the like. To the upper face of the 25 rail 18 and to the upper faces of the rail 17, the spacing strip 20 and finishing strip 21, finished plates 27^a may be applied, if so desired.

30 The forward ends of the beams 13, sills 10 and the forward faces of the forward studding 11 are preferably covered by trim, indicated at 28. The rectangular openings 29 thus formed are preferably closed by applying about the edges of the openings, stops 30 35 against which abut ply-wood panels 31 fitting the openings. Each panel is provided with a finger opening 32, so that it may be readily engaged for removal. These panels tend to conceal the space beneath the top and assist 40 in the formation of storage space 33 within which may be stored a bulk supply of the articles which are being exhibited upon the tops.

45 The double display cabinet construction is identical with that hereinbefore described with the exception of the fact that the studding 12^a corresponding to the studding 12 of the single display cabinet serves as the rear studding for both tops, and has applied to each face thereof a blackboard element 15. Also in this construction, the rail 18 has applied thereto a spacing strip 20^a and finishing strip 21^a corresponding to those employed with the rail 17. The grooves 50 55 19 formed by the rails 17 and 18 in each instance serve to receive the lower ends of advertising media 34 and 35. The advertising media 34 consist merely of framed blackboards having at their lower edges extensions of the framing strips, indicated at 36, which are adapted to enter in the grooves.

60 The advertising media 35 are intended for the reception of national full page advertising, such as is placed in standard magazines by practically all manufacturers and com-

70 prises a base 37 having a downwardly projecting rib 38 for engagement in the groove 19. Projecting upwardly from the base are a pair of spaced standards 39 provided adjacent their upper ends with inwardly projecting pivots 40. The pivots 40 engage opposite sides of a rectangular frame 41 to which is hinged at 42 a second similar frame 43. The inner edges of the confronting faces of the frames are rabbeted, as indicated at 44, and 75 associated with the frames is a panel 45 which fairly closely fits within the rectangular groove provided by the combination of the rabbets when the frames are in confronting relation. The openings 46 of the frames are 80 of such size that they will conveniently receive the advertisement to be posted and where the advertising medium 35 is employed with the single type of display cabinet, but a single advertisement is placed therein. 85 Where it is employed with the double type of display cabinet, two of the advertisements will be placed therein and the advertisements at opposite faces thereof will conform to the articles which are being exhibited upon the 90 top below.

95 It will be obvious that advertising mediums of this character may be readily shifted either longitudinally of the top upon which they are mounted or readily moved to a second display cabinet where they may be employed in the same capacity. Structures of this character permit the use of current and seasonable advertising without additional expense to the grocer. The blackboard may be used for 100 special advertisements, such as advertisements of bargain sales or articles which are not nationally advertised. The blackboards 105 may be used to display the prices of the articles in the associated bins and for the reception of any special advertising comment 110 which the vendor may desire to make.

115 Since the construction hereinbefore set forth is capable of a certain range of change and modification without materially departing from the spirit of the invention, I do not limit myself to such specific structure except as hereinafter claimed.

I claim:

120 1. A display counter having a top provided at its rear edge with a longitudinal groove, a back extending upwardly from the top and including a longitudinally extending framing member with a depending portion, the depending portion being disposed in advance 125 of the back and a partition, a vertical member secured to and projecting below the rear end of the partition and inserted into said groove, the upper end of the vertical member being inserted behind the depending member 130 carried by the back whereby said partition may be longitudinally adjusted along the top.

135 2. A display counter having a top provided at its rear edge with a longitudinal groove, a back extending upwardly from the top and 140

including a longitudinally extending framing member with a depending portion, the depending portion being disposed in advance of the back and a partition, a vertical member 5 secured to and projecting below the rear end of the partition and inserted into said groove, the upper end of the vertical member being inserted behind the depending member carried by the back whereby said partition may 10 be longitudinally adjusted along the top, the vertical member attached to the partition at its upper end being upwardly and outwardly beveled whereby the partition and member may be lifted to disengage the lower end of 15 the member from said groove and then turned to permit the upper end of the member being moved downward from behind said depending member of the back.

3. A display cabinet having a top provided 20 at its rear edge with a longitudinally extending groove, a back extending upwardly from the cabinet, a spacing member attached to the upper margin of the back and having a depending member attached to the front 25 thereof, the lower edge of the depending member being in spaced relation to the back and a slidable partition normally resting upon the top of the cabinet, the partition having at its rear end a vertical member projecting below the partition to engage in said 30 groove and projecting above the partition to engage in the space between the back and said depending member.

4. In a display cabinet, a top and a back 35 having opposed grooves, a partition slidable along the top to adjusted positions and having portions entering said grooves, the groove of the back permitting vertical movement of the partition to disengage the portion thereof 40 engaging the grooves of the top, the partition being oscillatably disengageable from the groove of the back when disengaged from the groove of the top.

In testimony whereof I hereunto affix my 45 signature.

ELDEN O. HENDERSON.
